(57) **CLAIM**

The ornamental design for quick release for use by divers,
as shown and described.

DESCRIPTION

FIG. 1 is a rear, top and right side perspective view of a quick release for use by divers showing our new design, the dotted lines showing end pieces to indicate other attachments can be used;

FIG. 2 is a right side view, the left side being a mirror image thereof;

FIG. 3 is a top view thereof;

FIG. 4 is a bottom plan view thereof;

FIG. 5 is a front elevational view thereof;

FIG. 6 is a rear elevational view thereof;

FIG. 7 is a right side view thereof with the magnets separated; and,

FIG. 8 is a cross-sectional view taken along the lines 8—8 of FIG. 2.

The broken line showing of environment in the drawings is for illustrative purposes only and forms no part of the claimed design.

1 Claim, 3 Drawing Sheets

FIG. 6
